UNITED STATES PATENT OFFICE.

JOHN C. SCHULTZ AND CLYDE D. McCANN, OF NEWTON, IOWA; SAID SCHULTZ ASSIGNOR
TO SAID McCANN.

ENGINE.

1,185,247.

Specification of Letters Patent.

Patented May 30, 1916.

Application filed July 14, 1913, Serial No. 779,061. Renewed April 17, 1916. Serial No. 91,767.

To all whom it may concern:

Be it known that we, JOHN C. SCHULTZ and CLYDE D. McCANN, citizens of the United States, and residents of Newton, in the county of Jasper and State of Iowa, have invented a certain new and useful Engine, of which the following is a specification.

The object of our invention is to provide an engine of simple, durable and inexpensive construction, of the type in which two pistons are mounted in a single cylinder.

More particularly, it is our object to provide an engine of the kind mentioned, having a crank shaft mounted below a cylinder and having the outer ends of the piston rods mounted in bearings above the level of the crank shaft and below the level of the middle of the cylinder.

Still a further object is to provide in such an engine having piston rods, pitmen and crank shafts, so arranged as to operate the shaft from the engine with a minimum of friction.

Still a further object is to provide such a device in which the parts are so arranged and constructed as to require a minimum number of parts and a minimum weight thereof.

A further object is to provide an engine of the class described in which the crank shaft is so mounted in the casing as to cause the crank shaft to work in oil at all times.

Our invention consists in certain details, in the construction, combination and arrangement of the various parts of the device, whereby the objects contemplated are attained, as hereinafter more fully set forth, pointed out in our claims and illustrated in the accompanying drawings, in which:

Figure 1 shows a vertical, longitudinal, sectional view through an engine embodying our invention. Fig. 2 shows a horizontal sectional view of the crank case, fly wheel, the crank shaft and the pitman working thereon.

In the accompanying drawings, we have used the reference numeral 10 to indicate the base on which our improved engine is mounted. Mounted on the base 10 is a frame or support 11. The lower end of the crank case is curved downwardly, as shown at 12, and is designed to contain oil 13. The cylinder 14 is suitably mounted and in it are two oppositely working pistons 15 to

which are secured piston stems or rods 16. Outside the cylinder, the piston rods 16 are bent downwardly and outwardly at 17, as shown in Fig. 1, and then are extended away from the pistons in horizontal lines, the outer ends 18 of said piston rods being mounted in suitable bearings 19. Mounted in the side walls 20 of the crank casing is a crank shaft 21, having two cranks 22 formed thereon and extending in opposite directions from each other, as shown in Fig. 2. Pivoted to the portion 18 of each piston rod is a pitman 23, which is also suitably connected with one of the cranks 22. Each pitman 23 is bent and therefore comprises two portions which form obtuse angles with relation to each other. The purpose of so bending the pitmen 23 is to clear the lower portion of the cylinder 14. On one outer end of the crank shaft is a fly wheel 24 and on the other end is a suitable gear wheel 25. It will be understood that ordinary valves and valve priming mechanism are provided for the cylinder 14. The crank case is provided with a cover 25 and said cover is so constructed that the crank works in oil.

Our engine has a number of advantages, many of which may be seen from the foregoing description. It is extremely compact and is made of few and simple parts. Our engine is of comparatively inexpensive construction and on account of the construction of the pitmen and the piston stems, we are able to transmit power from the piston to the crank shaft with a minimum of parts and a minimum of friction. Power is transmitted almost directly from the pistons to the crank shaft. The outer ends of the piston rods are mounted in bearings, whereby the pistons are held true to their path of travel. On account of the compact construction of our engine a single crank case is provided and a minimum of material and weight is necessary in building our engine. At the same time the working parts run in oil.

We claim as our invention:

1. In an engine, a support, a crank case thereon having a central downwardly extended portion designed to hold oil and to receive a crank shaft, a cover member for said case, a cylinder within said case having a portion projecting upwardly through said case, opposite pistons in said cylinder hav-

105

110

ing stems extending away from the pistons, and slidably supported at their outer ends, a transverse shaft in said case below the cylinder, having spaced oppositely extending cranks, and pitmen pivoted to the respective piston stems and to said cranks.

2. In an engine, a support, a crank case thereon having a central downwardly extended portion designed to hold oil and to receive a crank shaft, a cover member for said case, a cylinder within said case having a portion projecting upwardly through said case, opposite pistons in said cylinder having stems extending away from the pis-

tons, then downwardly and outwardly, then outwardly, and slidably supported at their outer ends, a transverse shaft in said case below the cylinder, having spaced oppositely extending cranks, and pitmen pivoted to the respective piston stems and to said cranks, said pitmen having portions bent outwardly to clear the ends of said cylinder.

Des Moines, Iowa, June 30, 1913.

JOHN C. SCHULTZ.
CLYDE D. McCANN.
